CONVEYER STAND

Ralph Lael, Lenoir, N. C.

Application November 20, 1936, Serial No. 111,946

1 Claim. (Cl. 248—351)

This invention relates to stands especially adapted for use in furniture factories employing endless conveyers for the conveying of head and foot ends of beds and like furniture and has for 5 the primary object the provision of a simple and inexpensive device which may be easily and quickly adapted to a head or foot end of a bed to engage with the conveyer guide rail to support said head or foot end and prevent the latter from contacting the guide rail and thereby obviate the danger of damaging or injuring the finish of the head or foot end during its movement by the conveyer.

With these and other objects in view, this invention consists in certain novel features of construction, combination and arrangement of parts to be hereinafter more fully described and claimed.

For a complete understanding of my invention, reference is to be had to the following description and accompanying drawing, in which

Figure 1 is a side elevation illustrating a stand constructed in accordance with my invention.

Figure 2 is a fragmentary front elevation illustrating a bed end equipped with my invention.

Figure 3 is an end elevation illustrating the same.

Figure 4 is a fragmentary sectional view showing the connection of my invention to the bed end.

Figure 5 is a fragmentary perspective view showing my invention adapted to a bed end and the latter located on an endless conveyer.

In the manufacture of bed ends it is a com-

mon practice to employ an endless conveyer, as shown at 1, for conveying the bed ends in an upright position the conveyer leaning against a guide rail 2. This way of handling bed ends subject them to damage by chafing against the 5 guide rail 2 and thereby destroys the finish. To prevent damage to the finish my invention can be readily adapted to a bed end and consists of a bar 3 to which is secured a plate 4. The plate 4 is located adjacent one end of the bar 3 and is provided with notches 5 and 6. Bed ends are provided with grooves 7 to receive ends of side rails of the bed and have located therein anchoring pins 8. In adapting my invention to the bed end the plate 4 is positioned in the recess 7 10 with the pins 8 occupying positions within the notches 5. The bar 3 then parallels the bed end and comes in contact with the rail 2 when the bed end is supported by the conveyer. It is to be understood that a pair of devices constructed in accordance with my invention is adapted to a 15 single bed end, as shown in Figure 5.

Stands of the character shown and described can be easily adapted to a bed end and removed therefrom after the removal of the bed ends from 20 the conveyer.

Having described the invention, I claim:

A stand comprising a bar and a plate secured to the bar adjacent one end and having notches to engage with anchoring pins of a bed end for 25 detachably securing the bar to said bed end and with the bar extending in parallelism with the bed end.

RALPH LAEL.
